ILLUMINATED SIGN

Arthur Richard Warner, London N. W. 8,
EnglandApplication March 9, 1938, Serial No. 194,772
In Great Britain March 15, 1937Section 3, Public Law 690, August 8, 1946
Patent expires March 15, 1957

8 Claims. (Cl. 126—124)

1

This invention relates to illuminated signs of the gaseous discharge type and has for its object to provide an improved form thereof.

In British patent specification No. 423,362 there is described an arrangement by which a luminous, gaseous discharge tube, fed with high frequency current, has a plate or similar conductor adjacent thereto and connected with one terminal of the tube. By applying to the tube a gradually increasing voltage, the discharge can be arranged to start at one end of the tube and to increase more or less slowly along its length until the tube is completely luminous.

It has been found, however, that sharp corners and abrupt bends such as are unavoidable in tubing bent into the form of a word or design, interfere with a smooth flow of light along the tube. When the head of the advancing light column reaches the bend, it pauses, and on resuming its movement tends to flash or jerk into the next portion of the discharge tube, thereby detracting from the effect.

According to a feature of the present invention therefore, I provide an adjustable conducting member which follows the convolutions of the tube along a major portion of its length. Preferably I employ a thin wire which is carried by the tube by means of small transparent insulating clips or by means of transparent or translucent adhesive.

In the accompanying drawing are shown by way of example certain details of the invention, and in which Figure 1 is a diagram illustrating the broad principles governing the application of the flexible conductor to a discharge tube, Figure 2 is a side view, partly in section of a sign, Figure 3 is a perspective view of a clip as used in the construction of Figure 2, Figure 4 is a side view of a further side, also partly in section, and Figure 5 is a detail showing a further method of arranging the flexible conductor.

In carrying the invention into effect, the manner in which the capacity wire must be disposed for optimum results depends largely on the diameter of the tubes, the kind of gas used, the gas pressure, the degree of abruptness and nature of the bend and on similar factors. As a guide, however, a description of the wiring of a U-shaped discharge tube as shown in Figure 1 may be mentioned.

The discharge tube 10 is provided with suitable electrode means by which a recurrently increasing high frequency potential may be applied to the tube. One of these electrodes is rep-

2

resented by the capacity of a wire or other flexible conductor 11, whilst the other is a conventional electrode at one end of the tube. The tube may be one of the type intended for operation by a high voltage low frequency alternating potential.

In considering the flow of current through a tube such as 10, the neon light will tend to flow smoothly along the initial straight portion from A to B and the provision of the wire 11 at this portion of tube will not noticeably affect the speed of flow, but is valuable in certain circumstances in increasing the brilliance of the whole tube when fully lit. When the head of the advancing light column approaches the curved portion of the tube its advance is checked. The provision of a wire, disposed comparatively close to the tube, from a point C slightly before or slightly beyond the commencement of the curved portion, assists the uninterrupted flow around the bend from C to D. It is usually found advantageous not to extend the wire closely along the tube for a short distance before the bend, that is, from B to C, as this results in assisting the flow along the straight portion where assistance is not needed and therefore helps to prolong the undesired pause at the bend. In practice, however, the wire can for convenience form one unbroken length by spacing portions thereof at sufficient distance from the tube as at 12 to render its capacity effect negligible.

If the head of the light column reaches a further bend in the tube of greater radius of curvature, as at E, it will again encounter a check and the wire may again be used to assist it to flow smoothly around the bend. As this bend is not so sharp the capacity due to the wire need not be so great as that described and can therefore be provided by either a short length of wire close to the tube or, as shown, a greater length further from the tube.

As a general rule the space between the wires and the tube should be greatest for the wires disposed near the starting or high potential end of the tube, the spacing gradually diminishing as the end portion is reached. In practice it is found that the capacity wire may often with advantage be run right along, and in contact with the surface of the last 25% to 35% of the tube. A 36 S. W. G. wire is very suitable for this end portion as it is easily secured to the tube by some transparent, insulating adhesive such as "durofix" and 28 S. W. G. tinned copper or resistance wire has been found very suitable for

the spaced wire 11. The space between wire and tube varies from $\frac{1}{16}$ " to $\frac{1}{4}$ ".

A simple embodiment of the invention is shown in Figure 2. In this figure a glass panel 13 is mounted within a suitable casing 14, and supports the tube 10. An inconspicuous mounting for the tube may be obtained by making a conical aperture in the panel and using a bead 15 as an anchorage for a binding wire 16.

The wire 11 may be attached to the tube 10 by means of small clips 17, Figure 3, of transparent material known under the trade name of "Celastoid." These clips comprise a portion 17a adapted to encircle the tube and a projection 17b in which an aperture 18 is adapted to receive the wire 11.

In the construction shown in Figure 4, the tube is mounted upon a member 19 by means of supports 20, which at their extremities carry saddles 21 to which the tube is secured by binding wires 22. The wire 11 may be supported by being passed through apertures 23 in the supports 20. Intermediate supports 24 may be used for carrying the wire 11 only.

In a sign of the type in which the tube is mounted closely behind a transparent portion of an otherwise opaque panel the construction shown in Figure 5 may be adopted. In this arrangement the tube is mounted on the panel by means of glass beads 15 and binding wires as previously described. Means indicated at 25 are provided for masking portions of the panel, and behind these portions are secured one or more flexible conductors in the form of a strip of metal 26. The strip may be supported at appropriate points by means similar to the supports 24, or by adhesive such as 27. Strip perforated zinc has been found very suitable.

The capacity wire system described is a great improvement on the plate system described in British specification No. 423,362, because:

(a) It results in a more smooth and even flow of light along the tube.

(b) The capacity wire can be mounted directly onto the tube and when thus mounted, is, to all intents and purposes, invisible to the observer. This makes it possible, where necessary, to mount the discharge tubes on glass panels, which is not possible with the plate system, as the irregularly shaped plate must be concealed.

(c) Modifications, adjustments and corrections are easily carried out at local portions of the tube. In this respect the plate system affords little or no scope.

What I claim and desire to secure by Letters Patent is:

1. An illuminated sign comprising a vapour discharge tube, electrodes for supplying a high frequency alternating current to said tube, and a flexible conducting member effectively connected to one of said electrodes and following the convolutions of the tube and constituting a capacity along the length thereof, said conducting member being adjustable in a direction towards or away from said tube over at least a portion of the length of said tube, whereby the capacity effect of said conductor may be varied to ensure an uninterrupted flow of the current about curved portions of the tube.

2. An illuminated sign comprising a vapour discharge tube, electrodes for supplying a high frequency alternating current to said tube, a flexible conducting member connected to one of said electrodes and following the convolutions of the tube, means engaging said tube for support-

ing said conducting member, said conducting member being adjustable in a direction towards or away from said tube over at least a portion of the length of said tube.

3. An illuminated sign comprising a vapour discharge tube, electrode means for supplying a high frequency alternating current to said tube, and a flexible conducting member effectively connected to one of said electrodes and following the convolutions of said tube, and clips of insulating material engaging said tube and supporting said conducting member, said conducting member being adjustable in a direction towards or away from said tube over at least a portion of the length of said tube.

4. An illuminated sign comprising a vapour discharge tube, electrode means for supplying a high frequency alternating current to said tube, and a flexible conducting member effectively connected to one of said electrodes and following the convolutions of said tube, said conducting member being adjustable in a direction towards or away from said tube over at least a portion of the length of said tube, and being arranged generally to approach said tube as the distance from said connected electrode increases whilst being arranged more closely to said tube at curved portions thereof.

5. An illuminated sign comprising a vapour discharge tube, electrode means for supplying a high frequency alternating current to said tube, and a flexible conducting member effectively connected to one of said electrodes and following the convolutions of said tube and constituting a capacity along the length thereof, an insulating panel supporting said tube, and means on said panel for supporting said flexible conducting member, said conducting member being adjustable in a direction towards or away from said tube over at least a portion of the length of said tube; whereby the capacity effect of said conductor may be varied to ensure an uninterrupted flow of the current about curved portions of the tube.

6. An illuminated sign comprising a vapour discharge tube, electrode means for supplying a high frequency alternating current to said tube, and a flexible conducting member effectively connected to one of said electrodes and following the convolutions of said tube and constituting a capacity along the length thereof, an insulating panel, and means on said panel for supporting said flexible conducting member and said tube, said conducting member being adjustable in a direction towards or away from said tube over at least a portion of the length of said tube, whereby the capacity effect of said conductor may be varied to ensure an uninterrupted flow of the current about curved portions of the tube.

7. An illuminated sign comprising a vapour discharge tube, electrodes for supplying a high frequency alternating current to said tube, and a flexible wire effectively connected to one of said electrodes and following the convolutions of the tube along the length thereof, said wire being adjustable in a direction towards or away from said tube over at least a portion of the length of said tube, and being arranged generally to approach said tube as the distance from said connected electrode increases whilst being arranged more closely to said tube at curved portions thereof.

8. An illuminated sign comprising a vapour discharge tube, electrodes for supplying a high frequency alternating current to said tube, and

a flexible wire effectively connected to one of said electrodes and following the convolutions of the tube along the length thereof, said wire being adjustable in a direction towards or away from said tube over at least a portion of the length of said tube, and being arranged generally to approach said tube as the distance from said connected electrode increases whilst being arranged more closely to said tube at curved portions thereof, and having its free end arranged in contact with said tube.
